UNITED STATES PATENT OFFICE.

FREDERICK W. LINDEMANN, OF ST. PAUL, MINNESOTA.

STEAM JOINT.

Application filed April 1, 1926. Serial No. 99,115.

The invention relates to improvements in joints for use in piping and has reference more particularly to such joints as those employed in connection with the steam chests 5 for the vertically movable pressing heads of garment presses.

The object of the invention is to provide a joint of exceptionally simple and inexpensive construction, yet one which will be 10 highly efficient and desirable for the purpose of feeding steam to the chest and exhausting the steam therefrom.

With the foregoing in view, the invention resides in the novel subject matter herein- 15 after described and claimed, the description being supplemented by the accompanying drawing.

Figure 1 is the top plan view showing the application of the invention to a garment press.

Figure 2 is a sectional view as indicated by line 2—2 of Figure 1, illustrating the joint in side elevation.

Figure 3 is a horizontal sectional view on 25 line 3—3 of Figure 2.

The drawing above briefly described, illustrates the preferred form of construction and while such construction will be hereinafter rather specifically described, it is to 30 be understood that within the scope of the invention as claimed, variations may be made.

The numeral 4 designates an elbow having an outer relatively large passage 5 opening 35 through its ends and an inner comparatively small passage 6. At one of its ends, this elbow is provided with an outer relatively large tube 7 which projects rigidly from said end and communicates with one end of the 40 passage 5, and within said outer tube 7, is a relatively small inner tube 8 which also projects rigidly from the elbow, the inner end of said tube 8 being in communication with one end of the inner passage 6, while 45 the outer end of said tube 8 projects beyond the tube 7. In the present showing, the tubes 7 and 8 have threaded connections 9 and 10 respectively, with the elbow 4, and the outer end of said tube 7 is threaded as 50 indicated at 11, to be tapped into an opening in the steam chest 12 of the movable presser head of a garment press, such a press being indicated in a general way in Figure 1.

An outer relatively large tube 13 and an inner comparatively small tube 14, project 55 rigidly from the end of the elbow 4, remote from the tubes 7 and 8, said tubes 13 and 14 communicating respectively with the passages 5 and 6. The outer sleeve 13 is preferably though not necessarily integral with 60 the elbow 4 and the tube 14 is by preference threaded into said elbow as indicated at 15, and the outer end of this tube 14 projects beyond the tube 13.

An elongated, substantially cylindrical 65 body 16 is provided with a cylindrical bore 17 opening through one of its ends and turnably receiving the tube 13, and said body 16 is formed with a steam inlet nipple 18 whose bore 19 is axially alined with the 70 first named bore 17, the inner end 20 of said bore 19 being counterbored and turnably receiving the end of the inner tube 14 which projects beyond the outer tube 13. Leading laterally from the bore 17, is a steam ex- 75 haust port 21 which is preferably threaded for engagement with an exhaust pipe 22, and it will be seen that the nipple 13 is shown provided with screw threads by means of which it may be readily coupled to the 80 steam supply pipe 23.

Means are provided for anchoring the body 16 to the frame of the garment press. In the present showing, a flange 24 is integral with and surrounds this body, and a 85 nut 25 is threaded upon said body for coaction with this flange in tightly securing the body in an opening in an appropriate bracket 26 which is secured by a bolt or the like 27 to the press frame. The threads 28 90 of the body 16, engaged by the nut 25, are also instrumental in providing for the attachment and adjustment of a packing gland 29, whose packing 30 prevents any leakage of steam between the body 16 and the 95 sleeve 13.

By the novel construction shown and described, steam may readily enter the chest 12 regardless of the vertical position to which the latter is moved, the steam passing through the bore 19, through the tube 14, through the passage 6 and through the tube 8, into said chest. Exhaust of steam from this chest takes place through the tube 7, the passage 5, the tube 13, the bore 100 17 and the port 21.

On account of the advantages existing for the exact construction herein disclosed, it is by preference followed. However, as above stated, variations may be made within the scope of the invention as claimed.

I claim:

1. A connection of the class described comprising an elbow having inner and outer relatively small and large passages, a tube 10 projecting rigidly from one end of the elbow and communicating at its inner end with said inner passage, said one end of said elbow forming an exhaust fluid inlet around said tube and being adapted for connection with a chamber, an outer relatively large tube and an inner comparatively small tube disposed in spaced concentric relation and both projecting rigidly from the other end of the elbow, the inner 15 end of said inner tube being in communication with said inner passage while the outer end of this tube projects beyond the outer end of said outer tube, a coupling body having a cylindrical bore turnably receiving said outer tube, said body having a 20 fluid inlet nipple whose bore is axially aligned with the first named bore, said nipple bore being counterbored at its inner end and turnably receiving the end of the inner tube which projects beyond said one outer tube, and a fluid outlet from said first named bore.
2. A structure specified in claim 1; said body having a peripheral flange adapted to abut one side of a support, said body being threaded substantially from said flange to the end of the body adjacent said elbow, and a nut and stuffing box threaded upon said body, said nut being cooperable with said flange to secure the body to the support, said stuffing box serving to prevent 30

leakage of fluid between said outer tube and said body.

3. A connection of the class described comprising an elbow having inner and outer relatively small and large passages, 45 two straight relatively large outer tubes projecting rigidly from the ends of said elbow and communicating with the ends of said outer passage, two straight relatively small inner tubes within said outer tubes and also projecting rigidly from said elbow, the inner ends of said inner tubes being in communication with the ends of said inner passage while the outer ends of said inner tubes project beyond said outer tubes, an elongated cylindrical body having a straight bore which turnably receives one of said outer tubes, said body having a fluid inlet nipple whose bore is axially aligned with the first named bore, said nipple bore being counterbored at its inner end and turnably receiving the end of the inner tube which projects beyond said one outer tube, and a fluid outlet from the first named bore. 50

4. A structure specified in claim 3; said body being externally threaded from its open end to a point between its ends and having an outstanding annular flange at the inner end of the screw threaded portion, a 55 nut threaded upon said body and cooperable with said flange to secure the body to its support, and a stuffing box threaded upon the open end of said body to prevent leakage of fluid between the body and said one outer tube. 60

In testimony whereof I have hereunto affixed my signature.

FREDERICK W. LINDEMANN.
